[57] **CLAIM**

The ornamental design for a baseball pom-pom, as shown.

DESCRIPTION

FIG. 1 is a front perspective view of a baseball pom-pom showing my new design;

FIG. 2 is a side view thereof;

FIG. 3 is a top plan view thereof;

FIG. 4 is a bottom plan view thereof; and,

FIG. 5 is an enlarged fragmentary view thereof, the tassels broken away for ease of illustration.

FIG. 1

FIG. 5
